UNITED STATES PATENT OFFICE.

MARY E. BIRNBAUM, OF SANTA BARBARA, CALIFORNIA.

STOVE.

SPECIFICATION forming part of Letters Patent No. 360,197, dated March 29, 1887.

Application filed June 23, 1886. Serial No. 206,008. (No model.)

To all whom it may concern:

Be it known that I, MARY E. BIRNBAUM, of Santa Barbara, in the county of Santa Barbara and State of California, have invented a new and useful Improvement in Stoves, of which the following is a specification, reference being had to the annexed drawings, forming a part thereof, in which—

Figure 1 is a front elevation, partly in section, of my improved stove. Fig. 2 is a vertical transverse section taken on line $x-x$ in Fig. 1. Fig. 3 is a plan view, partly in section, and Figs. 4 and 5 are detail views.

Similar letters of reference indicate corresponding parts in the different figures of the drawings.

The object of my invention is to construct a stove which may be placed in an arch in a partition of a building and arranged to heat two rooms.

My invention consists in a stove-body having an arched top and double walls at the sides and top thereof, and provided with a grate for containing the burning fuel, and with suitable doors and dampers at one side for introducing fuel, removing ashes, and regulating the draft.

The body A of the stove is preferably made rectangular in form, with an arched top, B, flattened to receive the short section of stove-pipe C, by which the stove-body is connected with the flue D. The side and top walls are made double, inclosing the air-spaces a, for the protection of the partition in which the stove is received. The air-spaces a are provided with damper-openings b, near their lower ends, and with openings c, discharging into the stove-top near the flue-opening.

The stove-back E is offset to increase the space in the interior of the stove, and is closed tightly, so that neither ashes, smoke, nor gas can escape from that side of the stove.

The front of the stove is provided with two pairs of doors, F G, which are hinged to the front of the stove near opposite sides. The doors G close upon a cross-bar, d, extending across the front of the stove, and inclose the space occupied by the fire and the grate, and the upper doors, F, close the combustion-chamber. Below the line of the bar d is formed an ash-pit, e, for receiving the ashes and cinders from the fire, and above the ash-

pit are supported two bars, f, whose ends extend downwardly at right angles and are received in sockets g, formed on opposite sides of the stove-body. When the stove contains a wood fire, the wood rests upon the bars f, and when coal is employed for fuel the basket-grate H is supported by the bars f, for containing the burning fuel. The bars f are apertured at n, to receive the lower ends of upright hooks or braces m, and a short slot, o, extends outward from the aperture n. The braces m are preferably flat and ornamental in design, having rounded lower ends to enter the apertures n, and slotted on opposite sides at p to engage the slots o. By entering the lower ends of the braces in the apertures n, and moving them forward so that the slots p engage the sides of the slots o, the braces will be held in position and will hold the grate in place.

The ash-pit e is extended beyond the front of the stove and provided with the removable apertured plate h, having the damper i, for closing its aperture. The bottom of the stove is to be placed on a brick foundation, and the front of the ash-pit e is preferably made hollow for containing air to prevent it from becoming overheated. A casing, l, similar in form to the projecting portion of the ash-pit e, is fitted to the back of the stove to improve its appearance and to serve as a foot-rest.

The stove is designed to be placed in an arch, J, formed in a partition between two rooms, the flue D being arranged in the partition for carrying away the products of combustion. In the flue D is placed the short length C of stove-pipe provided with a cross-bar, j, by which it may be moved up and down in the flue. The flattened top of the stove-body is provided with a groove, k, surrounding the smoke-discharge opening l, for receiving the lower edge of the pipe-section C when the stove is in place in the partition. The pipe-section C is pushed up in the flue by means of the cross-bar j, and when the stove is in its place, with the smoke-discharge opening l coinciding with the flue, the pipe-section is pulled into a groove in the top of the stove by reaching upward through the stove and grasping the cross-bar j.

Air admitted through the damper b prevents the heating of the partition-wall. The

fire in the stove-body is controlled by the damper *i* when the doors *F G* are closed, and it may be further controlled by opening or closing the said doors. The doors *F G* are 5 provided with knobs *m'*, for convenience in opening and closing them. The front and back of the stove will be suitably ornamented.

Having thus described my invention, what I claim as new, and desire to secure by Letters Patent, is—

1. The stove-body *A*, having double-walled sides inclosing air-spaces *a*, the dampers *b*, communicating with the air-spaces, the bars *f*, received in sockets *g* in the front and back of 15 the stove, the ash-pit *e*, damper *i*, and the doors *F G*, closing the front of the stove, all combined and arranged substantially as herein shown and described.

2. The combination, with the stove-body *A*, 20 provided with a groove, *k*, around the smoke-

discharge opening *l*, of the pipe-section *C*, adapted to be received in the groove *k*, and having the cross-bar *j*, substantially as described.

3. The combination, with the stove-body *A*, 25 provided with front and back heating-surfaces and side air-passages, as described, of the removable bars *f* and the basket-grate *H*, substantially as herein shown and described.

4. The combination, with the bars *f*, provided with the key-hole slot *n o*, of the upright braces *m*, having their lower ends notched at *p*, substantially as described, whereby provision is made for holding the grate in position on the said bars, as set forth.

MARY E. BIRNBAUM.
